ROOFING STRUCTURE

Julius Kahn and Walter F. Schulz, Youngstown,
Ohio, assignors to Republic Steel Corporation,
Cleveland, Ohio, a corporation of New Jersey

Application February 2, 1937, Serial No. 123,646

3 Claims. (Cl. 108—18)

This invention relates to sheet metal roofing and siding and is particularly directed to improvements in the joint construction therefor.

- An object of this invention is to provide a simple and efficient lap joint for metal roofing and siding sheets formed in such a manner that they may be readily overlapped one on the other and secured to the decking of the roof, to form a water tight structure free from leakage.
- Another object of this invention is to provide a jointed construction for metal roofing and sheathing which embodies metal sheets having a plurality of channels therein formed to possess great strength and stability, the members and parts of the channels being so arranged as to prevent creepage of water by capillary attraction to the underlying structure of the roofing, and at the same time permit free circulation of air through the joints to effect the dissipation of moisture therein.

Other objects and advantageous features more or less ancillary of the foregoing and the manner in which all the various objects are realized will appear in the following description which, considered in connection with the accompanying drawing, sets forth the preferred embodiment of the invention.

Fig. 1 is a perspective view illustrating the sheathing as applied to the decking of a roof or similar structure.

Fig. 2 is an enlarged sectional view in perspective of the joint construction taken on a plane indicated by the line 2—2 of Fig. 1.

Referring to the drawing, Figs. 1 and 2 illustrate a roofing structure comprising a plurality of metal sheets, generally indicated by the numeral 5, each of the sheets being interchangeable with the other and laid with their respective marginal edges in overlapped relation.

The marginal edge of each sheet is formed with a pair of spaced parallel ridges or ribs 6 and 7, preferably configured with convergent side walls and a flat top wall resembling the cross section of a truncated cone. The inclined legs, 8, 9, 10 and 11 of the convergent side walls terminate in a top wall or crown 12, parallel to the plane of the body of the sheet.

The legs 9 and 10, form a trough or valley 13, intermediate the ribs 6 and 7, the bottom portion 14 thereof, being disposed in the plane of the body of the sheet.

The leg 11 of the rib 7 is formed with an upturned arcuate flange constituting a relatively shallow trough 15, which extends throughout the

length of the sheet in the plane of the body portion thereof.

A rib or flute 16 of lesser altitude than the ribs 6 and 7 is formed in the sheet adjacent the base of the rib 6 and in spaced relation therewith, thus forming a trough or gutter 17 between the flute 16 and rib 6.

The opposite marginal edge of the sheet is formed with a ridge or rib 18, having inclined legs 19 and 20, which terminate in a flat top 10 or crown 21. The leg 19 is formed with an upturned arcuate flange which defines a shallow trough or gutter 22.

A rib or flute 23 is formed in the sheet adjacent the base of the leg 20, and in spaced relation therewith, the structure forming a trough or gutter 24, between the leg 20 and the flute 23. The rib 18, the gutter 22, and the flute 23 being constructed to overlie and snugly engage the outer inclined walls of the ribs 6 and 7, the gutter 17 and the trough 15, of the adjacent sheet when the roofing or sheathing is laid in assembled relation.

A rib 25 is formed in the sheet intermediate the ribs to strengthen the sheet, as well as enhance the appearance of the roofing.

Grooves 26 may be formed in the crown portions 12 of the ribs 6 and 7 and along each marginal edge of the top portion 21 of the rib 18, through which nails 27 or the like may be easily 30 and readily driven to secure the sheets upon the roof structure.

In applying the sheets upon a roof or similar structure, the marginal edges are laid in overlapping relation, with the legs 19 and 20 of the 35 rib 18 snugly embracing the legs 8 and 11 of the corrugations 6 and 7, and the grooves 22 and 24 firmly seated within the troughs 15 and 17. In such construction a multiplicity of barriers is provided which prevents the entry of moisture 40 between the sheets, and provides drainage channels for such water or condensation as might pass such barriers, further the flutes or ribs 16 and 23 are disposed to deflect moisture laden air currents upwardly and away from the exposed 45 seam of the joint, and will effect a low pressure area which creates a suction within the gutter 22 to counteract the capillary action between the overlapped portions of the sheets.

The rigidity of the joint structure and insured 50 intimate engagement of the overlapping portions of the sheets is attained by the provision of the upturned arcuate flanges and the engagement thereof with the surfaces of complementary configuration in the contiguous sheets. The effi- 55

cency of the seal is further aided by the rigidity of the portion of the sheet having the ribs 6 and 7 therein and the overlying portion of the sheet having the rib 18 therein.

- 5 In the assembly of the sheets the inclined side walls 19 and 20 of the uppermost sheet will embrace and be wedged upon the walls 8 and 9 of the subjacent sheet until the upturned flange on the free end of the lower sheet engages the base 10 of the gutter 24 where deflection of the leg 11 will be arrested and intimate engagement between the inclined legs 11 and 20 will be effected. With the structure embodying the ribs 6 and 7 thus rigidly united with the uppermost plate, no lateral movement will be effected between the overlying sections, and the free end of the leg 19 of the uppermost plate will be urged against the inclined wall 8 of the underlying plate, the arcuate flanged edge portion abutting the edge of the 20 gutter 17 increasing the pressure between such surfaces and thus effecting a fluid-tight seal.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention 30 as herein claimed.

We claim:

1. A lap joint for roof sheathing comprising two metal sheets overlapping at their marginal edge portions, the overlapping portions of the upper sheet having a raised central part flanked by downwardly diverging straight legs terminating in short upwardly and outwardly curved parts, the overlapped portion of the lower sheet having a trough flanked by substantially flat parts merging into downwardly diverging straight legs terminating in upwardly and outwardly curved parts, the central part of the overlapping portion of the upper sheet lying on the substantially flat parts

of the lower sheet, the downwardly diverging legs of both sheets being parallel and intimately pressing against each other, and the upwardly curved parts of the upper sheet nesting in the corresponding parts of the lower sheet, and means 5 passing through the central overlapping part of the upper sheet and through the lower sheet to hold them in assembled relation.

2. A lap joint for roof sheathing comprising two metal sheets overlapping at their marginal edge portions, the lower sheet having a longitudinally extending enlarged trough flanked by downwardly diverging substantially straight legs terminating in upwardly and outwardly curved portions forming small troughs and the upper sheet 10 having a raised central part spanning the trough of the lower sheet, said upper sheet having downwardly diverging substantially straight legs which overlie and intimately engage the corresponding legs of the lower sheet, one of the legs of the upper 15 sheet terminating in an upwardly and outwardly curved portion nesting in the marginal curved portion of the lower sheet.

3. A lap joint for roof sheathing comprising two sheets overlapping at their marginal edges, 25 the overlapped portion of the lower sheet having a large trough flanked by raised portions merging into downwardly extending legs, one of said legs terminating in a short upwardly and outwardly curved portion forming a small gutter, 30 a gutter and a small rib joining the other of said legs to the body of the lower sheet, the overlapping portion of the upper sheet having a raised central part covering the large trough and flanked by downwardly extending legs intimately engaging the legs of the overlapped sheet, a gutter and a small rib joining one of said legs to the body 35 of said sheet, and the other leg terminating adjacent the second mentioned gutter formed in the lower sheet.

40 JULIUS KAHN.
